UNITED STATES PATENT OFFICE.

JOSEPH A. COLLIN, OF COHOES, NEW YORK, ASSIGNOR OF ONE-HALF TO RUDOLPH ROULIER, OF COHOES, NEW YORK; JULIA COLLIN, ADMINISTRATRIX OF SAID JOSEPH A. COLLIN, DECEASED.

CAR-STEP-OPERATING MECHANISM.

1,307,850.

Specification of Letters Patent. Patented June 24, 1919.

Application filed April 5, 1918. Serial No. 226,927.

To all whom it may concern:

Be it known that I, JOSEPH A. COLLIN, a subject of Great Britain, residing at Cohoes, county of Albany, and State of New York, have invented certain new and useful Improvements in Car-Step-Operating Mechanisms, of which the following is a specification.

Reference may be had to the accompanying drawings, and the reference characters marked thereon, which form a part of this specification. Similar characters refer to similar parts in the several figures therein.

This invention relates to vehicles such as street railway cars having a folding-step which is automatically raised and lowered in substantial synchronism with the closing and opening of the car-door. It is desirable in such a car to have the door partly closed before the folding movement of the step begins.

The principal object of the present invention is to automatically operate the step in substantial synchronism with the operation of the door, while permitting an initial closing movement of the door before the folding of the step begins.

Other objects will appear in connection with the following description.

Figure 1 of the drawings is a top plan view of a broken-away corner portion of the body of a street railway car with the floor partly broken away to better show the step-operating mechanism.

Fig. 2 is a vertical cross section of the same taken on the broken line 2-2 in Fig. 1.

Fig. 3 is a vertical cross-section taken on the broken line 3-3 in Fig. 2, through the pivotal connection between the step-operating bracket and step-operating link.

Fig. 4 is a view in perspective of a connecting slide-block whereby the step-operating bracket is connected with the step-operating link.

Referring to the drawings wherein the invention is shown in preferred form, 1 is the platform floor forming part of a street car body from which floor depends a side-plate, 2, also forming part of the car-body.

Upon the side-plate, 2, is pivotally mounted at 3, a folding car-step, 4, shown in Fig. 2 in solid lines in lowered or unfolded posi-

tion, and indicated by dotted lines in folded or raised position.

Fixed upon the underside of the step, 4, is a bracket, 5, by means of which the step is raised and lowered.

A rotatory spindle, 6, forming part of the car-door-operating mechanism extends down through the platform floor and has fixed upon its lower end a crank, 7, whereby said crank is operatively connected with the car-door-operating mechanism.

The car door and its operating mechanism, except the spindle, 6, are not shown in the drawings, as their construction and manner of operation are well understood in the art and they form no part of the present invention.

For the purposes of the present invention, it will be sufficient to understand that the spindle, 6, is in such relation to the door and door-operating mechanism that the spindle is rotated in clockwise direction as the door is opened, and in the reverse direction as the door is closed.

The car-step, 4, is operated in substantial synchronism with the operation of the door by a link-connection, 8, between the bracket, 5, and the crank, 7, which link-connection is made up of a plurality of members, the innermost member, 9, being pivotally connected at 10, with the crank, 7.

The outermost-member, 11, of the link, 8, is made hollow, and contains a coil-spring, 12, which is adapted to engage a push-pin, 13, reciprocating in a slideway-aperture in said link-member.

The outer end of the link-member, 11, is slotted to form upper and lower ears, 14, and 15, respectively, and to form between said ears, a slideway for an ear, 16, on a slide-block, 17, the body of the slide-block being adapted to slide along the side of the ears, 14, 15, while its ear, 16, slides between said ears, 14 and 15.

The slide-block, 17, is secured in slidable relation to the link-member, 11, by means of a pin, 18, which extends through elongated slots, 19, in the respective ears, 14 and 15, and also extends through an aperture, 20, in the ear, 16, of the slide-block, 17.

Provision is thus made for a slide-motion of the slide-block, 17, longitudinally of the link, 8.

The ear, 16, on the slide-block, 17, is adapted to be operatively engaged by the push-pin, 13, but the length of the pin, 13, is so limited as to provide for substantial lost-motion between the pin and the slide-block, as shown by the space, 21, in Figs. 1 and 2.

The slide-block, 17, is pivotally connected with the car-step-operating bracket, 5, by means of a screw-bolt, 22.

10 After the car-door is closed, the link, 8, will be thrust outward by movement of the crank, 7, but this thrust-movement will be ineffective to raise the car-step until the lost-motion at 21, has been taken up.

15 After this lost-motion has been taken up, by which time the car-door will have been partly closed, the outward thrust of the link, 11, will be transmitted through the spring, 12, and push-pin, 13, to the slide-block, 17, 20 and thus to the step-operating bracket, 5, which is pivotally connected with the slide-block, 17, as above described.

The step will continue to be thus raised in synchronism with the closing movement of the car-door until the door is fully closed and the step fully raised.

To avoid the use of locking mechanism for the door and step, it is desirable to have the crank, 7, move slightly past its dead-center 30 in raising or folding the step.

By making one of the members of the link, 8, resilient, as by the spring, 12, I am able to permit such movement of the crank, 7, beyond a dead-center, without permitting 35 partial unfolding of the step, as the tendency of the step to unfold is overcome by the force of said spring.

What I claim as new and desire to secure by Letters Patent is—

40 1. The combination with a car-body; and a movable member operatively connected with car-door-operating mechanism mount-

ed upon said body; of a car-step pivotally mounted upon said body; a bracket connected with said step for raising and lowering 45 the same; and a link-connection between said bracket and said movable member of the car-door-operating mechanism, said link-connection having adjacent to said bracket a hollow member containing a plunger-slideway and 50 a slide-block-slideway; a slide-block movable in said slide-block slideway; a pivotal connection between said slide-block and said bracket; a coil-spring contained within said hollow member; and a plunger movable in 55 said plunger-slideway and yieldingly supported by said spring against longitudinal thrust of said slide-block.

2. The combination with a car-body; and a movable member operatively connected 60 with car-door-operating mechanism mounted upon said body; of a car-step pivotally mounted upon said body; a bracket connected with said step for raising and lowering 65 the same; and a link-connection between said bracket and said movable member of the car-door-operating mechanism, said link-connection having adjacent to said bracket a hollow member formed with longitudinally slotted ears and provided with a plunger-slideway; 70 a slide-block slidably mounted between said ears; a bolt inserted through the slots in said ears and through said slide-block whereby the slide-block is secured to said ears and guided in its movement longitudinally thereof; a pivotal connection between said slide-block and said bracket; a coil-spring contained within said hollow member; and a plunger yieldingly supported by said spring 75 against longitudinal thrust of said slide-block.

In testimony whereof, I have hereunto set my hand this 25th day of March, 1918.

JOSEPH A. COLLIN.
